(57) **CLAIM**

The ornamental design for a workbench, as shown and described.

DESCRIPTION

FIG. 1 shows a front view of a workbench;

FIG. 2 is a top view thereof;

FIG. 3 is a back view thereof;

FIG. 4 is a bottom view thereof;

FIG. 5 is a left-side view thereof;

FIG. 6 is a right-side view thereof;

FIG. 7 is a perspective view thereof;

FIG. 8 is a perspective view thereof, shown in an alternate state for ease of disclosure;

FIG. 9 is a perspective view thereof; shown in a second alternate state for ease of disclosure;

FIG. 10 is a perspective view thereof; shown in a third alternate state for ease of disclosure.

FIG. 11 shows a front view of an alternate configuration of the workbench, with the handles extended;

FIG. 12 is a bottom view thereof;

FIG. 13 is a top view thereof;

FIG. 14 is a left-side view thereof;

FIG. 15 is a right-side view thereof;

FIG. 16 is a back view thereof; and,

FIG. 17 is a perspective view thereof.

The broken lines in FIGS. 4 and 12 represent unclaimed environment only, and forms no part of the claimed design.

1 Claim, 11 Drawing Sheets
